PORTABLE COMBINED MOTION PICTURE PROJECTOR AND SCREEN

Max Kotler, Seaford, and Robert V. Nicolosi, Valley
Stream, N.Y., assignors to Elgeet Optical Company,
Inc., Rochester, N.Y., a corporation of New York

Application November 28, 1958, Serial No. 53,572

Term of patent 14 years

(Cl. D61—1)

The single figure is a perspective view of a portable combined motion picture projector and screen, showing our new design.

We claim:

The ornamental design for a portable combined motion picture projector and screen, substantially as shown.
